PROCESS FOR THE TREATMENT OF
HYDROCARBON OIL

Ralph H. Price, Galveston, Tex., and Vanderveer
Voorhees, Hammond, Ind., assignors to Stand-
ard Oil Company, Chicago, Ill., a corporation
of Indiana

Application February 23, 1935, Serial No. 7,688

7 Claims. (Cl. 196—49)

This invention relates to processes for the treatment of hydrocarbon oil and pertains more particularly to processes whereby very heavy hydrocarbon oils may be converted into lighter products in the gasoline boiling range.

It is an object of our invention to provide an integral process for the simultaneous treatment of relatively light hydrocarbon fractions including normally gaseous fractions, and relatively heavy liquid hydrocarbons, in order to cause the formation therefrom of desirable products in the gasoline boiling range.

A further object of our invention is to provide an improved process whereby relatively heavy charging stock in the nature of crude petroleum, topped crude, or the like, may be subjected to relatively drastic cracking in a single pass operation with the resulting formation of relatively large quantities of products in the gasoline boiling range, and clean cracking stock without deleterious coking of the apparatus.

More specifically it is an object of our invention to establish a process whereby relatively light hydrocarbons, including fractions which are normally incondensable, and relatively heavy hydrocarbons, such as crude petroleum or the heavier ends thereof, or the like, may be subjected to conversion into products in the gasoline boiling range by a single unitary process whereby at least a portion of the heat necessary to conduct the cracking of the heavy hydrocarbons is supplied by contact thereof with the lighter hydrocarbons, which have previously been heated to a high temperature to cause pyrolysis thereof and attendant formation of low boiling products in the gasoline boiling range.

According to our invention fresh gas to be treated, i. e. normally incondensable gas plus vapors ordinarily considered too light for inclusion in gasoline, is passed through a gas cracking zone wherein it is raised to a relatively high conversion temperature sufficient to cause the formation therefrom of benzol and other fractions in the gasoline boiling range, and the resulting highly heated gases and vapors including benzol and products of conversion, are directly contacted and intimately intermingled with the relatively heavy liquid hydrocarbon oil which it is desired to convert into lighter products in the gasoline boiling range, with the result that the hot gases and vapors are quenched below a gas cracking temperature and the heavy liquid hydrocarbon is raised to an active cracking temperature. The heavy liquid hydrocarbon is preferably first subjected to a separate heating process

wherein it is raised to a cracking temperature and subjected to a moderate amount of cracking, but need not necessarily be so preheated. In either case the quantity and characteristics of heavy liquid hydrocarbons are so controlled that the mixture is raised to a relatively high cracking temperature sufficient to cause conversion of said heavy liquid hydrocarbons into products in the gasoline boiling range at a rather rapid rate, by contact with the highly heated products from the gas cracking zone, the mixture of the hot gases and liquid hydrocarbons preferably taking place in an enlarged reaction zone wherein cracking of the heavy hydrocarbons takes place and deposition of coke will not be detrimental, and from which the lighter products including gasoline constituents and intermediate boiling oil suitable for clean cracking stock may be quickly and continuously removed without being subjected to undesirably great amounts of cracking. The hot gases and heavy liquid hydrocarbons may be introduced into the enlarged zone so as to commingle immediately on entrance or may be caused to flow countercurrent to one another in the said zone, or if desired the hot gases and heavy liquid hydrocarbons may be commingled in a common pipe line prior to entrance into the enlarged zone.

The cracked vapors from the enlarged reaction zone are then preferably fractionated to separate gases, gasoline distillate, and gas oil condensate, the former being passed to the gas cracking zone, either directly or after previous removal of any gasoline constituents or non-reactive gases, or both. The gas oil condensate is then passed through a separate cracking zone wherein it is subjected to a cracking temperature to cause the formation of additional gasoline constituents and gas oil cycle stock, which may be returned to the cracking zone already mentioned, or may be subjected to a separate cracking operation.

The hydrocarbon gas charged to the gas cracking zone preferably consists of or contains large amounts of ethane, propane, or butane, and may be derived from natural sources or from the cracking of liquid hydrocarbons, or any other source. Alternatively in place of utilizing cracked gas as a source of heat for the cracking of heavy liquid charging stock, or in addition to the use of such hot gases, hot reformed naphtha vapors, or hot vapors of other stock boiling below the gas oil boiling range, may be utilized. In this case the naphtha or other stock heated to the high temperature may be derived from an ex-

ternal source or may be that formed in the process itself, or both.

The heavy liquid hydrocarbon oil, such as crude oil, reduced crude, or the like, is preferably first 5 passed through a coil heating zone wherein it is raised to a moderate cracking temperature of, for example, around 850° F., with the attendant formation of the relatively small percentage of gasoline which can be formed without serious 10 coking trouble, and is then passed into the mixing zone into contact with the highly heated cracked gas or reformed naphtha, or other stock, and is therein raised to a considerably higher temperature of, for example, 925° F. to 950° F., or 15 even higher, with the resulting formation of additional quantities of gasoline constituents, and clean cracking stock for treatment as already specified.

By proceeding as described hereinbefore it is 20 possible to quench the hot products from the gas cracking reaction so as to check undesirable further conversion, while at the same time raising the liquid quenching oil to a relatively high oil cracking or viscosity breaking temperature, with 25 accompanying conversion of the heavy oil into gasoline and lighter products including intermediate boiling products suitable for use as clean cracking stock. Therefore even if a heavy liquid hydrocarbon in the nature of crude oil, topped 30 crude or the like is used for the quenching operation, it is assured that no virgin constituents thereof will pass off with the tar resulting from the gas cracking operation, in a subsequent separating step, which would be the result if the 35 temperature of the resulting mixture of hot cracked gases and quenching oil were not maintained at an oil cracking value for a sufficient period of time to effect the cracking of the liquid oil.

Another important advantage of the process, 40 from another point of view, is that by using such relatively light material as normally incondensable gases or reformed naphtha or other stock boiling below the gas oil range, as the source of heat for carrying out the cracking or viscosity breaking step by direct contact, it is assured that the 45 intermediate boiling oil obtained by the cracking or viscosity breaking of the heavier liquid hydrocarbon will be substantially free of cracked constituents resulting from any cracking process 50 other than that in which the heavy liquid hydrocarbon oil was cracked, since the constituents of the highly heated gases, benzol, or reformed naphtha mixed with the heavy liquid hydrocarbon to cause the cracking thereof, are mainly of so 55 low boiling point as to fall within the gasoline boiling range or a lower boiling range, whereby they will be vaporized and passed off overhead with the final desired gasoline distillate. Tarry constituents resulting from the gas cracking or 60 naphtha reforming steps are so high boiling as to pass off with the liquid residue instead of with the intermediate boiling oil. If reformed naphtha is the source of heat, the above-mentioned result is particularly assured by selecting the 65 naphtha to be reformed, so that substantially all of it boils at not over 450° F.

This process provides that the intermediate boiling oil, or clean cracking stock, so obtained 70 will be substantially homogeneous and will include only once-cracked constituents instead of a mixture of once-cracked and twice-cracked constituents, whereby the future cracking operation carried out on the clean cracking stock may be conducted under conditions more beneficial to 75 the treatment of once-cracked oil.

A further advantage is that by this procedure 5 relatively high conversion of the heavy liquid hydrocarbons to lighter products can be accomplished in a single once-through cracking operation without recycling, whereby the expense and deleterious coking effects of a recycling operation carried out on the heavy liquid hydrocarbons 10 may be avoided, while still securing even higher conversion thereof into gasoline and intermediate boiling oils suitable for use as clean 15 cracking stock.

The co-pending application of Ralph H. Price, Serial No. 630,256, pertaining to the Production 15 of motor fuel, describes and claims a somewhat related process according to which highly heated 20 gases from a gas cracking process are quenched by scrubbing with a heavier liquid hydrocarbon.

The above-mentioned and further objects and advantages of our invention and the manner of 25 attaining them will be more fully explained in the following description taken in conjunction with the accompanying drawing.

In the drawing Fig. 1 illustrates diagrammatically an oil cracking system embodying our invention and Fig. 2 illustrates in side elevation and 25 partly in section, a mixing nozzle for use in carrying out our invention.

Referring more particularly to the drawing, reference numeral 1 indicates the charging line 30 through which fresh relatively heavy charging stock, such as crude petroleum oil, topped crude or the like, is introduced. This charging oil is forced by pump 2 through indirect heat exchanger 3 and into the intermediate section 4 of combination tower 5, after having been also heated, if desired, either before or after passage through the indirect heat exchanger 3, by indirect heat exchange with other hot products of the operation, or by passage through an independent directly fired heating coil. In the section 40 4, which serves as a flash drum, the introduced charging oil is separated into vapors and liquid residue by aid of its contained heat, the vapors passing upwardly through the fractionating section 7 while the liquids pass downwardly, 45 are collected on trap-out tray 6, and are withdrawn from the flashing section through line 8. The liquids last-mentioned, e. g. topped crude, are forced by pump 9 through viscosity breaking furnace 10, wherein the oil is raised to a moderate 50 cracking temperature of, for example around 850° F., and is subjected to a moderate amount of conversion to products in the gasoline boiling range with the accompanying production of 55 quantities of gas oil and other intermediate boiling products suitable for use as clean cracking stock. The heated products pass from the viscosity breaking furnace through line 11 and into the reaction chamber 12, preferably being directed against a plate 13 located above the liquid 60 level therein, with such force as to break up the entering stream of oil into a spray of small droplets or particles.

In the reaction chamber 12 the stream of introduced heated heavy products is contacted and 65 thoroughly intermixed with a more highly heated stream of relatively light gases and vapors introduced through line 14 and preferably also directed against the plate 13 so as to assure 70 intimate contact between the two introduced streams of hydrocarbons. The temperature of the gases and vapors so introduced may be from 1000° to 1700° F. or more, while the temperature of the resulting mixture is most suitably in the range of 925° to 950° F., although it may have a 75

somewhat higher temperature provided the time the mixture is maintained at the high temperature is kept sufficiently short to prevent serious deposition of coke in the drum. In order to control the time of contact so that the desired cracking effect may be obtained, liquid residue is withdrawn from the base of the reaction chamber 12 by way of line 15, having control valve 16, at a rate sufficiently rapid to permit the desired cracking to take place; the faster the liquid residue is drawn off the shorter the time at which it is maintained at cracking temperature in the reaction chamber 12, and consequently the lesser the amount of cracking that takes place in that chamber. The withdrawn highly heated residue passes through the line 15 and control valve 16 into tar flasher section 17 of combination tower 5, preferably with a reduction in pressure, and therein separates into vapors and liquid residue, the former passing upwardly through the lower portion of crude flash section 4 wherein the rising vapors serve as a source of heat to aid in the stripping of lighter constituents from the introduced heavy oil, and are themselves at the same time subjected to fractional condensation, heavier constituents being condensed in the trap-out tray 6 in mixture with unvaporized portions of the introduced charging stock and being passed through the viscosity breaking heater 10 therewith. The unvaporized residual tar in the base of the tar flasher 17 is withdrawn from the process through draw-off line 19, as fuel oil or for any desired use.

The lighter constituents separated as vapors in the reaction chamber 12 pass off through the vapor line 20 and are preferably directed through pipe 23, and line 1 in combination with the fresh charge, into the fractionator 5. Alternatively the vapors may be introduced into the fractionator 5 at a higher level.

The vapors in the tower 5 undergo fractional condensation, condensate of the nature of gas oil suitable for use as a clean cracking stock collecting on trap-out tray 29. Condensate so collected is withdrawn through line 32, and is preferably forced by pump 33 through the heating coils of cracking furnace 34, wherein it is raised to a cracking temperature and subjected to conversion, preferably in the so-called vapor phase, to cause formation of additional products in the gasoline boiling range. The resulting highly heated products are then preferably passed through the line 35, having control valve 36, into the base of tar flasher section 17 of combination tower 5, but may instead, if desired, be passed through branch line 37 having control valve 38, into a separate evaporating tower 39 wherein the cracked products are separated into vapors and liquid residue, the former passing through conduit 40 into the crude stripping section 4 of combination tower 5 while the liquid residue or tar is withdrawn from the process through pipe 41. This alternative method of handling the cracked products from the furnace 34 has the advantage that the cracked tar may be separately withdrawn through line 41 while the tar derived from the fresh charging stock is withdrawn through line 19 from tar flasher 17. Still further separation of the products may be assured by closing valve 42 in line 40 and passing the vapors from evaporator 39 through valved line 43 into an entirely separate fractionating system, not shown, wherein light constituents in the gasoline boiling range are separated as vapors from heavier constituents as liquids, the former being removed and sep-

arately condensed while the latter may be recycled through the cracking furnace 34 or may be passed to an entirely separate cracking unit, not shown, wherein it is subjected to conversion into products in the gasoline boiling range, under optimum cracking conditions.

The lighter constituents of the vapors separated in the various sections of the combination tower 5 pass off from the top section thereof through conduit 44 and cooler 45 into a receiver 46, which is preferably maintained under a high pressure. In this receiver, or high pressure gas separator, relatively dry gases separate from liquefied hydrocarbons and are preferably withdrawn from the process through line 47. The liquid constituents collected in the receiver pass through conduit 48 having pressure control valve 49 into a low pressure receiver or separator 50, wherein a further separation takes place, the undesirably light constituents passing off as vapors through conduit 51 while the liquid constituents are removed as a desired distillate, e. g. gasoline, through draw-off line 52, forming a desired product of the process. Gasoline so obtained will be of relatively high anti-knock value, since it includes a percentage of benzol as well as vapor phase cracked gasoline constituents.

The highly heated gases and vapors contacted with the heavy oils introduced into reaction chamber 12 are preferably obtained by the cracking of hydrocarbon gases for the production of benzol, these hydrocarbon gases being either fresh gas from a natural source, refinery gases, cracked gases from the unit itself, or a mixture of some or all of these.

In carrying out this phase of the invention fresh gas from line 53 and/or recycled gases from low pressure separator 50 are passed through gas cracking furnace 54, under pressure generated by compressors 55 and 57', and in passing through the cracking furnace are raised to a gas cracking temperature preferably in the range of 1000° to 1700° F. and under a pressure of from atmospheric to 500 pounds per square inch or more, the conditions preferably being a temperature of from 1350° to 1700° F., and a pressure of from atmospheric to 100 pounds per square inch. With the higher pressures mentioned the lower temperatures may be used. The gases passing through the cracking furnace preferably consist of or contain large amounts of ethane, propane, or butane and these gases, under the conditions mentioned may be converted to benzol to an extent of two gallons or more per thousand cubic feet of original gas used. The resulting cracked gases pass from the cracking furnace at the temperature mentioned and then may travel directly through by-pass line 56 and the line 14 into reaction chamber 12, but preferably instead move through the enlarged reaction chamber 57, where additional conversion thereof takes place, and then pass through the line 14 to the reaction chamber 12 in contact with the heavy oil. Reference numerals 58 and 59 indicate valves whereby the necessary control of the gas flow may be obtained.

In place of, or in addition to the cracked gas from cracking furnace 54, heat may be supplied to the heavy oil in the reaction chamber 12 by reforming naphtha or gasoline having an undesirably low anti-knock value to form higher anti-knock gasoline constituents and introducing the highly heated reformed gasoline vapors into the reaction chamber 12. To accomplish this, fresh naphtha of relatively low anti-knock value

may be supplied from an external source through line 60 and be forced by pump 61 through reforming furnace 62 wherein the naphtha is raised to a relatively high cracking temperature, e. g., 5 in the range of 1050° to 1100° F. more or less, and is subjected to reformation with the resulting formation of relatively high anti-knock gasoline constituents. Naphtha for this purpose may suitably be a virgin fraction from crude oil with a 10 boiling range in the neighborhood of from 200° to 450° F. The highly heated reformed products pass through line 63 having control valve 64, and into the line 14 from which they pass inside the reaction chamber 12 in contact with the heavy oil introduced thereto through line 11. Instead 15 of, or in addition to the naphtha from the external source 60, naphtha from the fractionating section 7 of combination tower 5 may be used, this naphtha comprising both virgin and cracked 20 constituents. In this case the naphtha may be withdrawn from tray 65 in the fractionating section 7, by way of pipe 66 and be forced by pump 67 into the coils of the reforming furnace 62. The reforming of the naphtha may be carried out at 25 any well known pressure for that operation, but the outlet pressure on the reforming furnace is preferably in the neighborhood of 600 pounds per square inch, more or less.

According to an alternative method of operation 30 the vapors removed from the reaction chamber 12 through line 20, instead of being passed directly to the tower 5 are passed through conduit 22 into a separate fractionator 25, wherein fractional condensation occurs with the result 35 that constituents in the gas oil boiling range are condensed as reflux condensate, while lighter constituents comprising gas and gasoline pass overhead through vapor line 30 into the tower 5, for further fractionation with the vapors passing 40 through the last-mentioned tower. The reflux condensate collecting in the base of the fractionator 25 may then be withdrawn through line 27 and forced by pump 27' through the coils of cracking furnace 28 wherein the condensate is raised to a cracking temperature and subjected 45 to conversion under conditions of temperature, pressure and time best suited for the desired conversion thereof. This procedure would leave any virgin constituents of the charging stock for passage 50 through the cracking furnace 34 by way of line 32, after withdrawal from trap-out tray 29. In this connection it should be noted that the amount of volatile constituents released from the tar in chamber 17 and collecting on the trap-out tray 39 will be relatively small. As a result the cracking conditions in the furnace 34 could then 55 be adjusted to give the optimum cracking effect for that particular stock. As in the case of the cracked products from furnace 34 the cracked 60 products from furnace 28 may be passed through a separate evaporator and/or fractionator, not shown, to provide for the separate withdrawal of tar and the separate fractionation of the cracked vapors. Where the additional evaporator alone is used, the vapors may be directed from 65 that evaporator to the tower 5, while the cracked tar is separately drawn off from the process.

Valve 70 is provided for controlling the outlet pressure on the coils of furnace 28, while valves 70 71 and 72 control the flow of vapors from the reaction chamber 12 to either tower 5 or fractionator 25.

The pressure maintained in the reaction chamber 12 may be varied considerably depending 75 upon the operating conditions maintained in

other portions of the apparatus, but where hot products of a gas cracking operation are introduced into this reaction chamber the pressure therein must be lower than that maintained at the outlet of the gas cracking furnace so as to permit of the flow of the hot cracked gases into the reaction chamber. In general where a gas cracking furnace is used as a source of supply of heat the pressure in the reaction chamber may be maintained in the range of 50 to 100 pounds per square inch, while if the heat is derived from a reforming furnace only, the pressure in the reaction chamber may be considerably higher, for example in the neighborhood of 200 pounds per square inch, more or less.

The cracking conditions maintained in the heater or furnace 34 may be varied widely in accordance with the teachings of the prior art, but preferably these conditions are such as to carry out vapor phase cracking at a substantial rate, for example, the oil may be raised to a cracking temperature in the neighborhood of 950° to 975° F., under a pressure in the neighborhood of a few hundred pounds per square inch, e. g., 200 pounds per square inch. Under these conditions the conversion to gasoline per pass may fall in the range of 15% to 25%, ordinarily about 20% per pass, but in case the cracked products from the heater 34 are separately fractionated by being passed through line 37 to evaporator 39 and from vapor line 43 to a separate fractionating zone, not shown, wherein reflux condensate formed by fractionating the vapors is separately collected or diverted from the process. The cracking rates in the heater 34 may be carried considerably higher since the stock passing therethrough will then be mainly only once-cracked stock of less marked coke-forming tendencies. Under these circumstances the temperature may be considerably higher and the conversion to gasoline per pass 4 may be raised to 35% or more, particularly where higher pressures are used, e. g., 500 to 700 pounds per square inch or more. If the heater 28 is used the cracking conditions therein may be about the same as those of the heater 34.

In order to prevent undesirably great accumulation of gases in the apparatus it may be desirable to bleed off gases from the process from time to time through line 69, as well as from 47. A preferable method would be to separate hydrogen and methane from the recycled gases before passing them through the gas cracking furnace 54 and this may be done by any well known process such as low temperature fractionation or by scrubbing the gases with a selective solvent, such as light naphtha, which will tend to absorb the gaseous fractions which it is desired to re-crack while leaving the hydrogen and methane in vapor form to be drawn off from the process. The absorbed gases should then be liberated from the solvent liquid by heating so that it will not be necessary to pass the solvent itself through the gas cracking zone. The apparatus for carrying out the separation of hydrogen and other undesirably light gases from the gases and vapors to be passed 65 through the gas cracking furnace has not been shown on the drawing but may be constructed in accordance with the teachings of the prior art.

The viscosity breaking furnace 10 is preferably employed for a preliminary heating of the reduced crude with an attendant moderate amount of cracking of a viscosity breaking nature, but if desired this furnace may be by-passed by way of line 70', this being accomplished by proper manipulation of the control valves 71' and 72'. The 75

cracking furnace 34 and reforming furnace 62 may be followed by reaction chambers, not shown, if desired. At various points in the system cooling coils have been indicated in order to supply the necessary cooling action for fractional condensation of the vapors. In place of these cooling coils, which have not been indicated by reference numerals, cooling liquids may be pumped directly into the various chambers for refluxing purposes. When the indirect heat exchange coils are provided they may be used to preheat the fresh charging stock for the process if desired. Instead of passing the highly heated gases and the cooler heavy liquid hydrocarbons into the reaction chamber 12 separately they may be mingled in a common conduit outside the reaction chamber so as to be introduced as a mixture. In this case some additional cracking may take place in the conduit. Alternatively the heavy liquid oil may be introduced into the reaction chamber at a higher level than the hot gases so as to cause countercurrent contact to take place.

A particularly effective type of arrangement for mixing the heavy liquid oil to be cracked with the highly heated gases and vapors from the gas cracking zone, with a minimum of deleterious carbon deposition is illustrated in Fig. 2. In this figure reference numeral 12' indicates the wall of the reaction chamber and 11 and 14 the pipes through which the liquid oil and hot gases respectively, are introduced. Thirteen (13) is the plate against which the introduced liquids and gases impinge. The end of the pipe 11 is tapered to a nozzle 13 through which the oil is ejected at high pressure against the plate 13, while the end of the conduit 14 through which the hot gases are introduced is flared outwardly, funnel fashion, as indicated at 14, so that the gases are ejected at an angle to the surface of the plate, whereby any liquid oil particles which would tend to collect on the plate and deposit coke are quickly swept away into the body of the reaction chamber, from which any carbonaceous material may be removed with the liquid drawn off through line 15. With this arrangement intimate mixture of the liquid oil and hot gases is assured upon passage thereof through the restricted opening between the end of the pipe 14 and the plate 13.

50 By introducing the liquid oil at high velocity against a rigid splash plate the oil is broken up into a fog which is swept away by the stream of hot gases discharged at an angle to the plate around the periphery of the funnel-shaped enlargement of the gas inlet line. The splashing of the oil against the plate keeps it relatively cool and free from coke and any coke formed by heating of the oil droplets constituting the fog, through contact with the hot gases, is mostly formed within the droplet while suspended in mid-air and as a result will tend to be carried in finely divided form out into the main body of the drum or reaction vessel. As already stated this carbonaceous material may settle in the bottom of the drum and be carried out with the liquid oil, or some of it may pass overhead with the vapors through the vapor line 20.

55 While we have described a particular embodiment of our invention for the purposes of illustration, it should be understood that various modifications and adaptations thereof may be made within the spirit of the invention as set forth in the appended claims.

We claim:

75 1. The process of treating hydrocarbon oil

which comprises heating relatively light hydrocarbons, substantially all of which boil at a temperature of not over 450° F., to a relatively high cracking temperature to cause conversion thereof into hot vapors in the gasoline boiling range, introducing the resulting highly heated vapors and gases into a reaction zone and therein contacting them with relatively heavy liquid hydrocarbon oil introduced at a lower temperature from a separate source, the relative quantities and 10 temperatures of the highly heated gases and vapors and of the heavy oil being such that the temperature of the resulting mixture is considerably higher than that of the heavy oil at the time of its introduction, said temperature of 15 the resulting mixture being such as to cause cracking of said heavy oil, removing the resulting vapors from said reaction zone and fractionating them in a fractionating zone to separate gasoline constituents and an intermediate 20 boiling condensate, passing intermediate boiling condensate so obtained through a separate cracking zone in a stream of restricted cross-sectional area wherein it is raised to a cracking temperature, introducing the resulting cracked products 25 into a separating zone, passing vapors from said separating zone into said fractionating zone, introducing fresh relatively heavy charging stock into said fractionating zone in contact with the vapors therein, removing unvaporized portions 30 of said charging stock in mixture with relatively heavy condensate and introducing the mixture into said reaction zone as said heavy liquid hydrocarbon oil, and removing unvaporized constituents from said reaction zone and introducing them into said separating zone with an accompanying reduction in pressure, to cause flashing 35 thereof.

2. The process of treating hydrocarbon oil which comprises heating relatively light hydrocarbons, substantially all of which boil at a 40 temperature of not over 450° F., to a relatively high cracking temperature to cause conversion thereof into hot vapors in the gasoline boiling range, introducing the resulting highly heated vapors and gases into a reaction zone and therein 45 contacting them with relatively heavy liquid hydrocarbon oil introduced at a lower temperature from a separate source, the relative quantities and temperatures of the highly heated gases and vapors and of the heavy oil being such that the temperature of the resulting mixture is considerably higher than that of the heavy oil at the time of its introduction, said temperature of the resulting mixture being such as to cause cracking of said heavy oil, removing the resulting vapors from said reaction zone and fractionating them in a fractionating zone to separate gasoline constituents and an intermediate 50 boiling condensate, passing intermediate boiling condensate so obtained through a separate cracking zone in a stream of restricted cross-sectional area wherein it is raised to a cracking temperature, separating resulting cracked products into vapors and liquids in a separate vaporizing zone, 55 fractionating said vapors in said fractionating zone, introducing fresh relatively heavy charging stock into said fractionating zone, removing unvaporized portions of said fresh charging stock in mixture with relatively heavy condensate from said fractionating zone and introducing the 60 mixture into said reaction zone as said relatively heavy liquid hydrocarbon oil, removing liquid residue from said reaction zone and introducing it into a flashing zone under reduced pressure, 65 passing vapors from said flashing zone into said 70 75

fractionating zone, and utilizing gases derived from said fractionating zone, and of a lower boiling point than said gasoline distillate, as a source of said light hydrocarbons first-mentioned.

5 3. A process in accordance with claim 2 wherein the cracked intermediate condensate is introduced into said flashing zone for separation into vapors and liquids.

10 4. A process in accordance with claim 2 wherein in a fraction falling in the boiling range of about 200 to 450° F. is removed from said fractionating zone, passed through a separate heating zone in a stream of restricted cross-sectional area, wherein it is raised to a reforming temperature, 15 and resulting reformed products are introduced into said reaction zone.

10 5. A process in accordance with claim 2 wherein in said mixture of unvaporized fresh charge and heavy condensate is passed through a separate 20 heating zone wherein it is raised to a cracking temperature prior to the introduction thereof into said reaction zone.

25 6. A process of forming gasoline which comprises passing hydrocarbon gases through a gas cracking zone in a stream of restricted cross-sectional area wherein it is raised to a gas cracking temperature and subjected to conversion, introducing the resulting cracked products into a reaction zone, simultaneously passing heavy 30 naphtha falling in the boiling range of about 200 to 450° F. through a separate heating zone wherein it is raised to a reforming temperature and subjected to conversion, introducing the resulting reformed products into said reaction zone, 35 simultaneously introducing heavy liquid hydrocarbon oil into said reaction zone in such quantities that the temperature of the mixture in said zone is at a value sufficiently high to insure the cracking of said heavy oil but insufficient to continue said gas cracking operation, removing resulting gases and vapors from said reaction zone and fractionating them to form a desired gasoline distillate and a reflux condensate, passing reflux condensate so obtained through a separate 40 heating zone in a stream of restricted cross-sectional area wherein it is raised to cracking temperature and subjected to conversion, separating vapors from the resulting cracked products and fractionating them with said gases and 45 vapors first-mentioned, removing residue from said reaction zone and directing it into a flashing zone under reduced pressure, introducing resultant cracked reflux condensate into said flashing zone, removing vapors from said flashing zone 50

and fractionating them with said gases and vapors first-mentioned.

7. The process of treating hydrocarbon oil which comprises subjecting hydrocarbon gases to a cracking operation to form highly heated gases and vapors including benzol, introducing the resulting highly heated gases and vapors into a reaction zone, simultaneously introducing into said reaction zone a stream of heavy hydrocarbon oil at a cracking temperature considerably lower than that of said highly heated gases and vapors and thoroughly intermingling said gases and vapors with said heavy hydrocarbon oil whereby the gas cracking operation is terminated and the temperature of the mixture attains an oil cracking value materially higher than that of the introduced heavy hydrocarbon oil, so as to cause rapid conversion of said heavy hydrocarbon oil into lighter products including gasoline constituents and intermediate boiling oil suitable for use as clean cracking stock, quickly removing lighter gaseous and vaporous constituents substantially as rapidly as they are formed in said reaction zone, and subjecting gaseous and vaporous constituents so removed to fractionation to separate gases in mixture with gasoline, benzol and other light products falling in the boiling range of the final desired product, as vapors from gas oil and other relatively heavy constituents as liquid, separately removing said gases and vapors and said liquid, separately subjecting liquid so obtained to cracking temperature to cause conversion thereof into additional products in the gasoline boiling range, passing resultant cracked products into a separate vaporizing zone wherein separation of vapors from residue occurs, and fractionating resultant separated vapors in mixture with vapors removed from said reaction zone, removing liquid residue from said reaction zone and subjecting it to partial vaporization, bringing the vapors so obtained into contact with fresh relatively heavy charging stock containing lighter constituents, so as to cause partial vaporization of said charging stock, subjecting vapors so obtained to partial fractionation to segregate gasoline constituents from intermediate boiling oils in the nature of clean cracking stock, combining said intermediate boiling oils with the liquids derived from said fractionating step for cracking and introducing unvaporized portions of said charging stock into said reaction zone as the heavy hydrocarbon oil to be cracked.
